CLAIM

The ornamental design for a card holder for wallet holders, as shown and described.

DESCRIPTION

FIG. 1 is a perspective view of a card holder for wallet holders showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof in a use state;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is a perspective view thereof in open state.

The broken lines depict portions of the card holder for wallet holders and form no part of the claimed design.

1 Claim, 16 Drawing Sheets
